UNITED STATES PATENT OFFICE.

WILLIAM H. SHINN, OF CARNEGIE, PENNSYLVANIA.

PRESSED-STEEL JOURNAL-BOX FOR RAILWAY-CARS.

No. 860,254.

Specification of Letters Patent.

Patented July 16, 1907.

Application filed April 2, 1907. Serial No. 365,927.

To all whom it may concern:

Be it known that I, WILLIAM H. SHINN, of Carnegie, in the county of Allegheny and State of Pennsylvania, have invented a new and useful Improvement in Pressed-Steel Journal-Boxes for Railway-Cars, of which the following is a full, clear, and exact description, reference being had to the accompanying drawing, forming part of this specification, in which—

Figure 1 is a plan view of the blank of the lug-plate; Fig. 2 is a side elevation of the lug-plate after it has been bent and forged into shape; Fig. 3 is a front elevation of the same; Fig. 4 is a vertical sectional view of a journal-box showing the lug-plate in position and riveted to the body of the box; Fig. 5 is a plan view of the same; Fig. 6 is a bottom plan view of a modification of the lug-plate; Fig. 7 is a side elevation of the same; and Fig. 8 is a rear elevation of the same.

My invention relates to an improvement in journal-boxes for railway cars and it consists in a journal-box having a body portion formed of pressed steel and having a lug-plate provided with depending flanges or lugs and a hinge flange or lug, this plate and these flanges or lugs being formed in one piece, the plate being of such form as to act as a reinforcement to the box, as is hereinafter more fully set forth.

In Fig. 1 of the drawing, 2 represents the blank from which the lug-plate is formed. This blank is cut to the shape shown in the drawing and may be provided with rivet holes 7. The wings *a b* are then bent under or over the leaf *c*, and the blank is then pressed by drop forging, or by other suitable means, to the finished lug-plate shown in Figs. 2, 3, 4, and 5. The blank 2, in addition to the wings and leaves *a b*, and *c*, is provided with front leaves *d d*, and *e*. The effect of the drop forging or pressing is to bend the leaves *c* downwardly to a substantially vertical position, to weld the wings *a b*, and the leaf *c* together and to corrugate the same, thus forming the depending side lugs 3. The front leaves *d d*, and *e* are bent upwardly, the shorter leaf *e* being bent vertically upward and its outer end horizontally, or slightly downwardly, backward, thus forming the spring base flange or rest 5, against which the spring of the box lid is adapted to press, and the leaves *d d*, being curled upwardly and backwardly forming the hinge flange or socket 4. The lug-plate 8 so formed is adapted to be part of a pressed steel journal box, such a journal box 6 being shown in Figs. 4 and 5 of the drawings. This box is formed in one piece, having a butt or overlapping seam in the upper portion 9 of the body. The lug-plate 8 fits under the upper portion 9 of the journal box 6 and the plate and box are

united by welding or by rivets or bolts, or other equivalent means. This brings the corrugated flanges or lugs 3 of the plate 8 within the corrugated side depending flanges or ribs 10 of the journal box, the side lugs 3 serving as a reinforcement to the ribs 10, between which ribs or corrugations is the groove or cavity 11 for the reception of the arch bar bolts. The depending flanges or lugs 3 also serve as rests or stops for the brasses or bearings of the journal box. At the forward end of the lug-plate 8, on each side of the lug 4, are lugs 12 which are bent downwardly from the body of the blank 2 in the drop forging operation and serve as a rest for the stop wedge of the journal box.

In Figs. 6, 7, and 8 I have shown a modification in which the hinge flange or lug 4^a and the spring base flange or rest lug 5^a are formed by drop forging of a single solid lug integral with the plate 8^a in which a cavity 13 for the pintle of the hinge is drilled. The corrugated side depending flanges lugs 14 are also formed by drop forging in solid parts of metal integral with the plate 8^a. In place of forging the plate 8^a it may be cast, but I prefer the pressing or forging.

The advantages of my invention will be appreciated by those skilled in the art. It is well known that the hinge lugs and spring back rest of journal boxes are liable to injury or breakage. Heretofore in pressed steel journal boxes, such lugs have been generally formed in a separate piece which has been welded or riveted to the top reinforcing plate of the box. By my improvement I am able to form the plate and these lugs in one piece. By corrugating the side lugs I am enabled to reinforce the bolt groove in a pressed steel box at that point where the greatest strength is required. By my improvement the box is strengthened and lightened.

Having thus described my invention, what I claim and desire to secure by Letters Patent is

1. In a pressed steel journal box having a body portion, a reinforcing lug plate adapted to be secured to the top of the box, said lug plate being provided with depending flanges and with an upwardly extending hinge flange, the flanges and plate being formed in one piece. 90
2. In a pressed steel journal box having a body portion, a reinforcing lug plate adapted to be secured to the top of the box, said lug plate being provided with depending flanges and with upwardly extending hinge flange and spring base flange, the flanges and plate being formed in one piece. 95
3. In a pressed steel journal box comprising a body portion formed of a single piece of pressed steel, the upper portions of which meet at the top, forming a lap or seam, a lug plate lapping the seam of the body portion and secured thereto, said lug-plate being provided with depend- 100

ing corrugated side flanges, depending front flanges and upwardly extending hinge and spring base flanges, the lug-plate and flanges being formed in one piece.

4. In a pressed steel journal box, comprising a body portion formed of a single piece of pressed steel, the upper portions of which meet at the top, forming a lap or seam, a lug plate lapping the seam of the body portion and secured thereto, said lug plate being provided with depending side flanges, an upwardly extending hinge flange, and

downwardly extending lugs which serve as a rest for the 10 stop wedge of the journal box, the flanges, lugs, and plate being formed in one piece.

In testimony whereof, I have hereunto set my hand.

WILLIAM H. SHINN.
